UNITED STATES PATENT OFFICE.

PETER LORD, OF MONTREAL, QUEBEC, CANADA, ASSIGNOR OF FIFTY-FIVE ONE-HUNDREDTHS TO EUGENE LANNEGRACE, OF MONTREAL, QUEBEC, CANADA.

VALVE.

1,150,779.

Specification of Letters Patent. Patented Aug. 17, 1915.

Application filed April 25, 1913, Serial No. 763,565. Renewed January 14, 1915. Serial No. 2,279.

To all whom it may concern:

Be it known that I, PETER LORD, a subject of the King of Great Britain, and a resident of the city of Montreal, in the Province of Quebec, in the Dominion of Canada, have invented certain new and useful Improvements in Valves; and I do hereby declare that the following is a full, clear, and exact description of the same.

10 The invention relates to improvements in valves, suitable for steam, water or the like and has for its object to devise a valve having a minimum number of parts and to improve upon the construction of a fluid 15 valve in such a manner that it will be perfectly fluid tight, cheap and easy to produce and durable as to wear and tear.

One of the chief features of the invention is a connection between the valve and 20 its stem whereby said valve will always adapt itself correctly to its seat even though the closure to the open top of the casing, including the stem operating member, may not be exactly in alinement with the valve 25 seat.

In the accompanying drawings, with the aid of which the invention will be better understood, Figure 1 is a vertical section showing the invention applied to a well 30 known style of globe valve for heating systems. Fig. 2 is a sectional plan view on the line A—B, Fig. 1. Fig. 3 is a perspective detail of the valve and stem. Fig. 4 is a vertical sectional view showing the 35 invention applied to a faucet. Fig. 5 is a sectional plan view on the line C—D of Fig. 4, and Fig. 6 is a sectional elevation of a slightly modified form of connection between the valve and stem.

40 Like numerals of reference indicate corresponding parts in each figure.

Referring to the drawings and particularly to Figs. 1, 2, 3, 1 is the valve casing, here shown of globe shape, having the inlet 45 2 and outlet 3.

4 is a conical valve seat within the casing 1 between the inlet 2 and outlet 3.

5 is an upward extension of the valve casing 1 having the internal thread 6 in 50 alinement with the valve seat 4 and the finished upper surface 7.

8 is the bonnet having the flange 9 contacting the surface 7, the thread 10 engag-

ing the thread 6 of the casing, and the nut 11 by which the bonnet is screwed into the 55 casing 1.

12 is a cylindrical orifice passing concentrically through the bonnet 8 and terminating at its lower end in the conical surface finished plug seat 13.

60 14 is a plug whose body portion is shaped to nicely fit the orifice 12 and whose lower end is fashioned into a conical surface finished flange 15 adapted to nicely fit the plug seat 13. The plug 14 has a central threaded orifice 16 leading from the lower end into a cavity 17 and its upper end above the body part is provided with a squared portion 18 and a threaded extremity 19.

20 is the operating handle having a 70 squared hole in the center to fit the part 18 of the plug.

21 and 22 are a pair of lock nuts threaded on to the plug extremity 19 and adapted to 75 secure the handle in place on the plug and at the same time to pull said plug upwardly so that its conical lower end 15 engages the surface 13 fairly tightly, a spring washer 23 being disposed between the said nuts and the upper surface of the handle in order to 80 maintain said contact.

24 is the valve having a substantially spherical recess 25 approximately central of 85 its height and width and also having the guiding wings 26.

27 is the valve stem having the left hand thread 28 engaging the threaded orifice 16 in the plug 14 and also having the ball 29 at its lower end substantially fitting the recess 25 in the valve, thus accomplishing 90 a ball and socket connection between said stem and valve.

29^a is a guiding lug extending laterally from the stem 27 and at its outer end engaging a vertical guide way 30 cut in the 95 wall of the valve casing 1.

In the use of this invention it will be seen that on turning the handle 20 to the right hand as usual in closing a valve, the stem 27 will, by reason of its left hand thread, be 103 forced downwardly, as the handle turns the plug 14 and the plug in turn operates on the stem, said stem being prevented from rotating by reason of the lug 29^a engaging the guide way 30. The downward travel of the 108 stem of course pushes the valve 24 on to the

seat 4, and it must be here stated that it is very important that the ball and socket connection between stem and valve should be substantially central of the height and width of said valve and of the seat when the valve is closed, as I have found in experiments that this is really the only practicable method by which the valve will accommodate itself perfectly, that is to say, without 10 leaking, on to its seat in circumstances where the bonnet and upper parts are not exactly in concentric alinement with the valve seat, which frequently happens in the manufacture of all valves.

15 In Fig. 4, the invention is shown applied to a faucet, there being practically no difference in this arrangement except that the inlet and outlet are changed as necessary in order to accommodate the invention to a 20 faucet.

It must be noticed that with this invention, the valve can be made of very little height and therefore neater in appearance. In raising the valve by turning the handle 25 to the left, the upper end of the thread 28 travels farther into the recess 17.

In Fig. 6 a still further modification of the ball and socket connection is shown, but here again the center of such connection is 30 substantially central of the height and width of the valve and seat, the only difference being that the ball is on the valve and the socket on the stem. The first described form, however is much preferred.

What I claim is:—

1. In a valve, the combination with a casing having a valve seat therein, of a valve stem longitudinally movable in said casing and having a leg engaging a vertical slideway in said casing, a valve adapted to engage said seat, ball and socket means connecting the lower end of said stem with the valve, substantially central of the height and width of said valve (and of the seat when the valve is closed) and a rotary member having screw connection with said stem for imparting longitudinal movement thereto.

2. In a valve, the combination with a casing having a valve seat therein, a valve stem having a lateral leg intermediate of its length engaging a vertical slideway in said casing and having a ball shaped lower end, a valve adapted to engage said seat and having a ball recess central of its height and width (and of the height and width of the seat when the valve is closed) said lower end being secured in said recess; and a rotary member having an internal thread engaging an external thread on said stem for imparting longitudinal movement to the latter.

Signed at the city of Montreal, Quebec, Canada, this 5th day of April, 1913.

PETER LORD.
